MACHINE FOR SLOTTING HEELS

George Hazelton, Leicester, England, assignor to
 United Shoe Machinery Corporation, Paterson,
 N. J., a corporation of New Jersey

Application January 9, 1936, Serial No. 58,327
 In Great Britain March 23, 1935

10 Claims.

(Cl. 12—42)

This invention relates to the manufacture of shoes and is illustrated herein as embodied in a machine for forming slots in the breasts of heels.

In United States Letters Patent No. 2,046,454, granted July 7, 1936 on an application filed in the names of Hazelton, James and Bacon, there is disclosed a machine for forming in the breast of a pre-finished Cuban heel made up of a plurality of lifts, a slot which is V-shaped in cross section and extends transversely of the breast of the heel adjacent to the attaching face of the heel, the slot being of suitable size to receive the rear end of the short outsole of the shoe to which the heel is later to be attached. A shoe comprising the above-mentioned heel and outsole is disclosed in detail in United States Letters Patent No. 2,027,431, granted January 14, 1936 on an application filed in the names of Hazelton, James and Bacon.

There is a tendency for the heel to move rapidly against the slot-forming cutter of the above machine with the result that the heel material adjacent to the slot is sometimes scorched or burned. The feeding of the heel too rapidly against the cutter is partly due to the tendency of the cutter to draw the work but is largely the result of the natural desire on the part of the operator who manually controls the movement of the heel, to hasten the operation.

In order to control the speed of presentation of the heel to the cutter and in accordance with a feature of this invention, there is provided a machine comprising a cutter, a carrier for a shoe part such, for example, as a heel, manually operated means for moving the carrier, and mechanically operated means for enabling the carrier to be moved toward the cutter by the manually operated means at a predetermined speed. In the illustrated machine, movement of the heel which is positioned upon the carrier, toward the cutter to form a slot such as above described, may be stopped at any stage of the operation, but the speed of the carrier and therefore the speed of the heel toward the cutter cannot be varied. The speed at which the carrier can be moved is so chosen that the movement of the heel toward the cutter is sufficiently slow to insure that the heel shall not be scorched and that a well-defined slot is formed in the heel.

The invention will be better understood and appreciated after reading the following description in connection with the accompanying drawings, in which

Fig. 1 is a side view of the illustrated machine, parts of which have been broken away;

Fig. 2 is an enlarged plan view of the work carrier of the machine;

Fig. 3 is a detail front view of the lower end of a post which supports the work carrier;

Fig. 4 is a sectional view taken along line IV—IV of Fig. 3;

Fig. 5 is a detail sectional view taken along line V—V of Fig. 2; and

Fig. 6 is a perspective view of a heel the breast of which has been slotted by the use of the above machine.

The illustrated machine is described with reference to forming a slot 20 (Fig. 6) in the breast of a pre-finished Cuban heel 22 comprising a plurality of lifts 24. The slot 20 is V-shaped in cross section and is formed and arranged to receive the rear end of a short outsole (not shown).

The machine comprises a rotary barrel cutter or saw 26 (Fig. 1) which is mounted upon a shaft 28 and has a plurality of elongated cutting teeth 30, a carrier 32 for supporting the heel 22, and mechanism for moving the heel against the cutter after it has been positioned upon and clamped to the carrier, thereby forming the slot 20 in the breast of the heel.

The carrier 32 comprises a work plate 34 (Fig. 5) and a slide 38 which is secured by screws 36 to the work plate and which is mounted for movement along an undercut slideway 40 of a guide plate 42. The heel is positioned widthwise and lengthwise upon the carrier 32 by a pair of gages 44 (Fig. 2) adjustable along slideways 46 of the carrier upon turning a screw 48 which is rotatably mounted upon the carrier. Right-hand and left-hand threaded portions 50, 52 of the screw 48 are in threaded engagement with the respective gages 44, and when the screw is turned the gages are moved equal distances toward and away from a central plane 54 of the carrier 32.

In order to insure that the heel 22 shall be stably supported upon the carrier 32, a plate 56 having a convex heel-engaging face 58 is secured to the carrier by a screw 60 (Fig. 2). The gages 44 comprise upwardly extending arms 62 (Fig. 1) which are provided with abutments 64 (Fig. 2) formed to engage opposite sides of the heel 22 for positioning the same widthwise upon the carrier 32, the arms 62 also being provided with stops 66 against which the breast of the heel is forced to position the heel lengthwise upon the carrier. Since the heel 22 is tapered the abutments 64 tend to force the heel against the plate 56 as they are pressed against the sides of the heel.

In order to force the heel against the stops 66 there is provided a clamp 68 which is pivotally

mounted upon trunnions 70 (Fig. 1) extending from an upstanding boss 72 of the carrier 32. The clamp 68 comprises a pad 74 pivotally mounted upon the forward end of a rod 76 which is adjustably secured through the provision of a set screw 78, within a bore of a housing 80 to which an upstanding handle 82 is attached. A spring 84 (Fig. 2) is provided to force the heel-engaging pad 74 against the forward portion of the rod 76 thereby insuring that the pad shall not turn upon the rod under its own weight when the clamp 68 is raised to an inoperative position. The clamp 74 is forced against the heel by a spring 86 (Fig. 1) the upper and lower ends of which are secured to the housing 80 and to the guide plate 42, respectively. The trunnions 70 are so positioned with relation to the spring 86 that when the rear end of the housing 80 is swung against a projecting lug 88 of the carrier 32, the spring 86 is moved to a horizontal position and retains the housing in engagement with the lug 88.

The carrier 32 has a depending extension 90 (Figs. 1 and 5) which extends through a slot 91 (Figs. 2 and 5) in the guide plate 42 and is provided with a recess 92 constructed and arranged to receive the non-threaded shank of a lead screw 94 which is in threaded relation with a thrust collar 96 (Fig. 1) secured within a post 98. The guide plate 42 is secured to the upper end of the post 98 and is also rigidly connected to the post by a pair of braces 100.

The carrier 32 is operated by a hand lever 102 which is fulcrumed upon a stud 104 secured to the guide plate 42 and which has an elongated slot 106 (Figs. 2 and 5) shaped to receive a pin 108 secured to the carrier 32. The handle 110 of the lever 102 may be manually moved back to its starting position but is usually swung toward the operator after the slot 20 has been formed in the heel 22 under the action of a spring 112. One end of the spring 112 is attached to an extension 114 of the lever 102 and the other end of the spring is secured to a rod 116 attached to the guide plate 42. The carrier 32 is moved toward the cutter 26 by swinging the lever 102 rearwardly, that is, toward the cutter 26, and is moved away from the cutter through the above-described mechanism. Movement of the carrier 32 toward the cutter 26 is limited by engagement of a stop screw 118 which is in threaded relation with the lug 88 of the carrier, against a shoulder 120 of the guide plate 42. Movement of the carrier 32 away from the cutter 26 is limited by engagement of the depending extension 90 of the carrier 55 with the rear end 122 (Fig. 2) of the slot 91.

The speed of presentation of the work to the cutter 26 is limited by mechanism which will now be described. A pair of pulleys 124, 126 (Fig. 1) are loosely mounted upon the lead screw 94 at the opposite sides of the depending extension 90 of the carrier 32. The pulleys 124 and 126 are continuously operated by belts 128, 130, respectively, which are driven by pulleys 132, 134, respectively, keyed to a drive shaft 136. Clutch disks 138, 140 positioned adjacent to the pulleys 124 and 126, respectively, are pinned to the lead screw 94. It will be noted that the belt 128 is crossed and the pulley 132 is relatively small in order that the pulley 124 may be rotated at a low speed in a counterclockwise direction, as viewed from the front of the machine. The belt 130 is open and engages a large pulley 134 in order to drive the pulley 126 at a relatively high speed in a counterclockwise direction. The lead screw 94 is normally stationary since neither of the pulleys 124,

126 is forced against its corresponding clutch disk.

When the operator swings the lever 102 toward the cutter 26 the depending extension 90 of the carrier 32 forces the pulley 124 against the clutch disk 138 thereby causing the lead screw 94 to rotate in a clockwise direction as viewed from the left in Fig. 1. As the lead screw 94 rotates it moves in the direction of its axis of rotation toward the cutter 26 at a predetermined speed depending upon the pitch of the thread of the lead screw and upon the speed of rotation of the drive shaft 136. After the stop screw 118 (Fig. 1) has engaged the shoulder 120 of the guide plate 42, the pulley 124 ceases to press against the clutch disk 138 thereby causing the lead screw 94 to come to rest.

It is customary, as above stated, for the operator to remove his hand from the lever 102 after the slot 20 has been formed thereby causing the lever to return to its starting position under the action of the spring 112. Movement of the lever 102 away from the cutter 26 causes the depending extension 90 of the carrier 32 to force the pulley 126 against the clutch disk 140 thereby causing the lead screw 94 to rotate rapidly in a clockwise direction and thereby permitting the carrier 32 to return quickly to its starting position. As above stated, movement of the carrier 32 away from the cutter 26 is limited by engagement of the depending extension 90 with the forward end 122 (Fig. 2) of the opening 91 formed in the guide plate 42.

It is desirable that the mechanism supported by the post 98 be swung to one side preparatory to removing the cutter 26 from the shaft 28. Accordingly, the post 98 has a bracket 142 secured to its lower end, the bracket being mounted upon a bearing 144 supported by a slide 146. The slide 146 may be adjusted to different heightwise positions along a guideway 148 formed in a frame 150 secured to a column 152, by turning a set screw 154 which is rotatably mounted in the frame 150 and is in threaded engagement with the slide 146. The post 98 is held in the upright position shown in Figs. 1 and 2 by a pin 156 secured to the slide 146 and constructed and arranged to engage within an arcuate recess 158 (Fig. 3) formed in the post 98. The pin 156 is clamped against the bottom of the arcuate recess 158 to retain the post 98 in an upright position, through the provision of a screw 160 which is in threaded engagement with an angle arm 162 (Fig. 4) pivotally connected to a collar 164 mounted upon the pin. When it is desired to swing the post 98 about the bearing 144 preparatory to removing the cutter 32 from the machine, the screw 160 is loosened and the post 98 is swung in a clockwise direction (Fig. 3) after the angle arm 162 has been pushed rearwardly out of the path of movement of the post 98.

The cutter shaft 28 is mounted in bearings 166 housed within the upper end of the column 152 and is rotated by a pulley 168 which is keyed to the shaft and is operated by a belt 170.

Having described my invention, what I claim as new and desire to secure by Letters Patent of the United States is:

1. A machine for operating upon shoe parts having, in combination, a cutter, a carrier for a shoe part, manually operated means for moving the carrier, and mechanically operated means for enabling the carrier to be moved toward the cutter by said manually operated means at a predetermined speed.

2. A slotting machine having, in combination,

5 a cutter, a carrier for a heel, means for positioning the heel upon the carrier, manually operated means for moving the carrier, and mechanically operated means for enabling the carrier to be moved toward the cutter by said manually operated means at a predetermined speed to form a slot in the heel.

10 3. A slotting machine having, in combination, a cutter, a carrier for a heel, means for positioning the heel upon the carrier, manually operated means for moving the carrier toward the cutter, and mechanically operated means for limiting the speed of the carrier moved toward the cutter by said manually operated means, the operation 15 of the means for limiting the speed of the carrier being dependent upon the operation of the manually operated means.

20 4. A slotting machine having, in combination, a rotary saw, a carrier for a heel, means for positioning the heel upon the carrier and for securing the heel to the carrier, manually operated means for moving the carrier toward and away from the saw, and mechanism rendered operative by said manually operated means for permitting the carrier 25 to be fed at a relatively low speed toward the saw and at a relatively high speed away from the saw.

25 5. A slotting machine having, in combination, a rotary saw, a carrier for a heel, means for positioning the heel upon the carrier and for securing the heel to the carrier, manually operated means for moving the carrier toward the saw to form a slot in the heel, and mechanism rendered operative by said means for limiting the 30 rate of feed of the carrier to insure the formation of a properly formed slot in the heel.

40 6. A slotting machine having, in combination, a rotary saw, a carrier for a heel, means for positioning the heel upon the carrier and for securing the heel to the carrier, a lead screw movable lengthwise of its axis, a driven pulley loosely mounted upon said screw, a clutch disk secured to said screw, and manually controlled means for causing the carrier to force the pulley against the disk thereby causing the screw to move toward the saw and to regulate the speed of the heel upon the carrier toward the saw.

45 7. A slotting machine having, in combination, a rotary cutter, a carrier having an extension, means for positioning a heel upon the carrier and for securing the heel to the carrier, an internally threaded thrust collar, a lead screw in threaded engagement with the collar and having its axis of rotation arranged at a substantial angle to the plane of rotation of the cutter, a pulley loosely mounted upon the lead screw and positioned adjacent to the extension of the carrier, means for driving the pulley, a clutch member secured to the lead screw, and a lever for moving the carrier lengthwise of the lead screw to cause the exten-

sion of the carrier to force the pulley against the clutch member thereby moving the screw lengthwise of its axis and permitting the carriage to be fed at a predetermined rate toward the cutter.

5 8. A slotting machine having, in combination, a rotary saw, a carrier having an extension, means for positioning a heel upon the carrier and for securing the heel to the carrier, an internally threaded thrust collar, a rotatable lead screw in threaded engagement with the collar and having its axis of rotation arranged at a right angle to the plane of rotation of the saw, a pair of spaced pulleys loosely mounted upon the lead screw and positioned at opposite sides of the extension of the carrier, means for driving the pulleys in opposite directions upon the lead screw, a pair of clutch members secured to the lead screw adjacent to the respective pulleys, a lever for moving the carrier in the direction of the axis of rotation of the lead screw to cause the extension of the carrier selectively to force one of the pulleys against an adjacent clutch member thereby causing the clutch member to move lengthwise of said axis with the lead screw and permitting the carriage to be fed by said lever at 20 a speed equal to the speed of the screw in the direction of its axis of rotation.

30 9. A slotting machine having, in combination, a rotary barrel saw, a carrier having an extension, means for positioning a heel upon the carrier and for securing the heel to the carrier, an internally threaded thrust collar, a lead screw in threaded engagement with said collar and having its axis of rotation arranged at a substantial angle to the plane of rotation of the saw, 35 a pulley loosely mounted upon the lead screw and positioned adjacent to the extension of the carrier, means for driving the pulley, a clutch member secured to the lead screw, a lever for moving the carrier in the direction of the axis of rotation of the lead screw to cause the extension of the carrier to force the pulley against the clutch member thereby causing the screw to move along said axis and permitting the carriage to be fed at a predetermined speed toward the 40 cutter, and a frame upon which the carrier and the thrust collar are supported, said frame being mounted for swinging movement to permit the cutter to be removed from the machine.

45 10. A machine for operating upon shoe parts having, in combination, a cutter, a carrier for a shoe part, manually operated means for effecting relative movement between the carrier and the cutter to cause the cutter progressively to operate upon the shoe part, and mechanically 50 operated means rendered operative by said manually operated means for controlling the rate of said relative movement between the carrier and the cutter.

55 GEORGE HAZELTON. 60
